US0D1026593S

(12) **United States Design Patent** (10) Patent No.: **US D1,026,593 S**
(45) Date of Patent: ** May 14, 2024

(54) **PLIERS**

(71) Applicant: **Ming Chieh Wu**, Taichung (TW)

(72) Inventor: **Ming Chieh Wu**, Taichung (TW)

(**) Term: **15 Years**

(21) Appl. No.: **29/841,701**

(22) Filed: **Jun. 8, 2022**

(51) LOC (14) Cl. **08-05**

(52) U.S. Cl.

USPC **D8/52**; D8/72

(58) **Field of Classification Search**

USPC D8/51-58, 72

CPC B25B 7/123; B25B 27/0035

See application file for complete search history.

(57) **CLAIM**

The ornamental design for pliers, as shown and described.

DESCRIPTION

FIG. 1 is a perspective view of pliers showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is another perspective view thereof showing the pliers in an open state.

The broken lines depict portions of the pliers in which the design is embodied that are not considered part of the claimed design.

1 Claim, 8 Drawing Sheets

FIG. 2

FIG. 3

FIG. 4

FIG. 5

FIG. 6

FIG. 7

FIG. 8
